MEANS FOR UNBLOCKING LENSES

Donald Dodkin, Southbridge, Mass., assignor
to American Optical Company, Southbridge,
Mass., a voluntary association of Massachusetts

Application February 13, 1942, Serial No. 430,730

2 Claims. (Cl. 62—1)

1
This invention pertains to improved means for unblocking lenses or materials having the character of lenses. In the optical industry, lenses that require an optical surface are of necessity ground and polished. The grinding and polishing operation necessitates some means for holding the lens on a given axis so that the true optical surface will result.

The method of securing the lens on a given axis is ordinarily obtained by securing the lens blank to a lens block, which lens blank is secured to said block by a bonding material. One of the conventional bonding materials now in wide use is "pitch." After one surface of the lens blank is adequately treated, it is necessary to remove the lens or the lens blank from the lens block. Heretofore, the lens or lens blank was removed from the lens block by placing the lens and lens block under a stream of water, or by subjecting it to some cooling medium such as by placing it in an ice box. While various methods for unblocking the lens or lens blank from the lens block are used, they all require the amount of time that ordinarily involves minutes.

The present invention contemplates the use of a refrigerant to cool a fluid bath so that the lens block may be suitably immersed in the fluid bath to provide the necessary cooling of the pitch between the lens or lens blank and the lens block. The ordinary pitch now in use for the purpose of blocking lenses has a coefficient of expansion about ten times as great as that of the average lens. It can be reasonably said that the coefficient of expansion ratio between pitch and glass is about ten to one. It will therefore be seen that by cooling the lens block, the pitch and lens medium will both be cooled, but because of the ten to one ratio, the pitch will contract much more rapidly than the lens so that the lens will be freed from the pitch.

Employing the present method, a fluid bath is used in which the lens blocks are substantially immersed. Because of the mobility of the fluid, which is cooled by a refrigerant, there results an intimate contact between the cooled fluid and the lens block. Since the fluid will have an equal distribution about the lens block, a substantially uniform cooling of the lens block will produce substantially uniform cooling of the pitch and the lens so that the contraction of the pitch, which is more rapid than the glass, will cause a clean severance between the glass and the pitch.

It is therefore an object of the invention to provide an improved means of unblocking a lens or lens blank by subjecting the lens block to the

action of a cooling medium, which medium is cooled by a gaseous or quasi-gaseous refrigerant.

It is a further object of the invention to provide a means of unblocking lenses by cooling the lens blocks in a bath of fluid having a very low freezing point, said bath being cooled by a gaseous or quasi-gaseous refrigerant.

A further object of the invention is to provide a refrigerating tank supplied with a cooling agent which lowers the temperature of a fluid bath in intimate contact with the lens block.

A further object of the invention is to provide novel means of unblocking lenses or the like by subjecting lens blocks to a fluid medium, which fluid medium is directly cooled by a stream of refrigerant.

A further object is to provide a lens unblocking apparatus having means for suspending the lens blocks in a liquid bath which is cooled by a refrigerant.

In the drawings:

Fig. 1 is a sectional view of a tank somewhat like the tank shown in Fig. 3 except that a refrigerant chamber therein is separated from the compartment carrying the fluid cooling medium.

Fig. 2 is a sectional view taken along lines 2—2 of Fig. 3 showing a multi-orificed nozzle immersed in the cooling fluid below the lens blocks.

Fig. 3 is a top view of Fig. 2 showing the relative position of the orificed nozzle in relation to the lens blocks within the cooling tank.

Referring to the drawings and more particularly to Fig. 1, a cooling tank 4 has an outer insulating layer 5 on the sides and the bottom. The tank has a lower chamber 6 with a plurality of spaced baffles 7 secured to the bottom of the tank. A spacing member 8 separates the lower chamber 6 from the upper chamber 9. The spacing member is supported by ribs 10 on the underneath side 40 thereof, with the spacing member preferably being made of thin metal and having a water-tight connection with the side walls of the metallic liner 11 of the tank 4.

A rack 12 is formed of longitudinally disposed wires 13 which are U shaped so that the free ends thereof rest on the top side of the spacing member 8. Cross wires 14 are shaped substantially the same as the longitudinal wires 13 and disposed laterally thereof and are sufficiently close together so that a series of square-shaped supports are provided by the longitudinal and cross wires to permit the shank 15 of the lens blocks 16 to be inserted therein so that the lens blocks are supported with the lenses 16 above the fluid 17.

The spacing member 8 has a series of baffles 19 suspended therefrom and interposed between the spaced baffles 7 secured to the bottom of the tank so that a tortuous path is provided as indicated by the arrows in the lower chamber 6. A conduit 20 has the free end thereof for connection to a refrigerant supply tank. A control valve 21 for controlling the flow of the refrigerant into the chamber 6 of the tank 4 connects conduit 20 to a pipe coupling 22 so arranged that the jet 23 which is on one end of the pipe coupling is disposed internally of the chamber 6. A lock nut 24 on the pipe connection 22 holds the jet 23 in place within the lower chamber 6. An opening 25 is provided in the lower chamber 6 through the metallic liner 11 and the insulation 5 so that an escape is provided for the chamber 6 to eliminate any substantial back pressure when the refrigerant is supplied in the lower chamber.

Fig. 2 shows a tank 26 having an inner liner 27 and an insulating portion 28 on the sides and bottom of the tank 26. A pipe connection 29 is connected to the fluid chamber 39 and has a nozzle 31 connected on one end thereof, which nozzle and pipe connection are secured to the metallic liner 27 by means of nuts 32 and 33. The nozzle 31 has a plurality of jets 34 on the underneath side thereof, and a cap 35 on the end of the nozzle 31 so that the refrigerant entering the tank 26 through the pipe connection 29 will be urged through the jets 34 and into the fluid 36 in the tank 26.

A rack 37 is formed in much the same manner as the rack 12 in Fig. 1. The rack 37, shown in Fig. 2, is used to support the lens blocks 38 thereon so that the lenses 39 may be close to the surface of the cooling fluid 36.

Fig. 3 is a top view of the section shown in Fig. 2 and shows the tank 26 having the inner liner 27 with the insulation 28 on the outside thereof. In Fig. 3 the rack 37 is shown having the squares therein which provide the support for carrying the lens blocks 38 and the lenses 39, with said lenses 39 being supported above the surface of the cooling fluid 36.

Fig. 3 shows three nozzles 31 which are connected to the pipe couplings 29 with the caps 35 connected on the free ends of the various nozzles. The number of nozzles, the number of jets in the nozzles, the location of the jets in relation to the lens blocks, and the distance of the lens blocks above the jets, are simply illustrative and any arrangement or dimension of parts may be employed depending upon the desired results.

The refrigerant which enters the jet in Fig. 1 will pass over the tops of the baffles 7 and underneath the bottom of the baffles 19 so that there is a definite path for the refrigerant. The fluid 17, in Fig. 1, touches one wall of the chamber 6 so that the fluid 17 may be sufficiently cooled so that when the lens blocks are disposed in the fluid, there will be a substantially uniform cooling of the lens blocks.

In Figs. 2 and 3, the refrigerant has a pressure exerted in the direction shown by the arrows x so that the refrigerant is ejected from the jets 34 into the fluid cooling medium 36.

The preferred refrigerant for use in conjunction with the present invention is set forth as being carbon dioxide (CO_2), since carbon dioxide is ordinarily readily available, and is easy to handle. The carbon dioxide is ordinarily stored in a compression tank and may be in a liquid or gaseous form. When the control valve 21 is opened (Fig. 1) the CO_2 flows in the direction

shown by the arrows through the lower chamber 6 so that the liquid medium 17 may reach a sufficiently low temperature to properly cool said liquid 17.

In Fig. 2, the liquid refrigerant coming from the jets 34 and the nozzle 31 is preferably carbon dioxide, which is utilized as a refrigerant as set forth in reference to Fig. 1, except that in Fig. 2 the refrigerant emerges through the jets 34 directly into intimate contact with the cooling fluid 36 so that the cooling fluid acts as a medium to chill the lens blocks 38.

While carbon dioxide has been set forth as a preferred refrigerant, other refrigerants may be used such as ethane C_2O_6 , propylene C_3H_6 , and propane C_3H_8 . The cooling fluid 17 or 36 may be ethyl-alcohol which has a freezing point of approximately $-114^\circ C.$ or methyl alcohol which has a freezing point of approximately $-97^\circ C.$ Ethylene glycol may be mixed with water so that approximately 52.5% of the mixture is ethylene glycol, which will result in a cooling fluid having a freezing point of about $-40^\circ C.$ Kerosene having a freezing point of about $-56^\circ C.$, and acetone having a freezing point of about $-95^\circ C.$ may also be used as a cooling fluid.

From the foregoing, it will be seen that where the liquid refrigerant is used, the liquid changes to a gas to absorb the latent heat of vaporization. Under any condition, whether a liquid or gas is used, it will still be expanding when in operation so that an adequate cooling is obtained. The refrigerants utilized may be compressed into a tank and when the critical pressure is obtained within the tank, or compression chamber, the gas becomes a liquid.

The cooling fluid used, under any condition, would ordinarily be such that it would not freeze when used in an unblocking system as set forth herein in conjunction with any of the refrigerants set forth in the application or with any other suitable refrigerant.

While the present disclosure shows that the lens blocks only, are immersed in the cooling fluid, under certain conditions the entire lens block and its lens may be immersed in the liquid bath. However, the present disclosure is sufficient to show that the mobility of the cooling liquid will cause intimate engagement with a major portion of the lens block so that adequate cooling being throughout the lens block will cause a rapid severance of the lens from the pitch due to the difference in the coefficient of expansion between the pitch and the lens.

In utilizing the present disclosure, the lenses are unblocked rapidly and the sides of the lenses or lenses blanks that engaged the pitch will be substantially, if not entirely, free from any pitch particles.

The present invention is more rapid and more efficient than any commercial method heretofore known and reduces the time for unblocking a single lens from that of minutes to that of seconds.

Having described my invention, I claim:

1. In a device of the character described for unblocking lenses, the combination of a receptacle adapted to contain a fluid, a rack in the receptacle for supporting at least one lens block having a lens adhesively secured thereto, said rack being spaced from the bottom of the receptacle, a cooling fluid in the receptacle to a level sufficient to cover the rack and immerse substantially the whole of the lens block without contacting the lens adhesively secured thereto,

nozzle means extending within the receptacle and disposed below the rack, said nozzle means having a plurality of jets therein, and a source of refrigerant connected with the nozzle means, the refrigerant being held under compression at the source and adapted upon ejection from the jets of the nozzle to expand and chill the cooling fluid.

2. In a device of the character described for unblocking lenses, the combination of a receptacle adapted to contain a fluid, a rack in the receptacle for supporting at least one lens block having a lens adhesively secured thereto, said rack being spaced from the bottom of the receptacle, a cooling fluid in the receptacle to a level sufficient to cover the rack and immerse substantially the whole of the lens block without contacting the lens adhesively secured thereto, said fluid having a freezing point lying between -40° C. and -114° C., nozzle means extending within the receptacle and disposed below the rack, said

nozzle means having a plurality of jets therein, and a source of refrigerant connected with the nozzle means, the refrigerant comprising CO_2 held under compression at the source and adapted upon ejection from the jets of the nozzle to expand and chill the cooling fluid.

DONALD DODKIN.
